UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924. Serial No. 751,762.

To all whom it may concern:

Be it known that I, CLINTON M. SEARL, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a division of my application filed April 21, 1924, Serial No. 707,796.

It is desirable in lasts of this type that 20 the last be capable of being easily collapsed so that it may be removed from a shoe without injury to the lining of the shoe and without stretching the shoe out of place.

In lasting a shoe the last is held upside down—that is, with the sole side uppermost—and inasmuch as a great deal of pressure is put on the toe of the last during the lasting operation, this tends to collapse the last, and consequently one of the objects of my invention is the provision of a construction in which the last is capable of 30 withstanding the stresses to which it is subjected during the lasting operation without collapsing, but may be readily collapsed by the operator when desired.

In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

45 In such a construction, the greater the distance the pins are below the axis of the last when the last is extended, or the greater the distance they are above the axis of the last when the last is collapsed, the more 50 resistance the last will offer to collapse or extension, but this distance is limited inasmuch as the pins must be located in the last body itself, and in the case of wooden lasts the pins must be kept at an appreci-

able distance from the bottom or sole face 55 owing to the danger of splitting the last when the same is in use or when being moved from extended position to collapsed position or vice versa.

In the present construction I have provided an arrangement for attaching the two last parts to each other whereby an effect 60 is obtained which is as efficient as the lowering of the pins in the above-outlined construction to the danger point, the resistance to collapse or extension offered by my last being very materially increased, without, however, necessitating placing of any pins at a point where they are likely to cause the last to split.

70 It is one of the especial objects of my invention to provide a last in which the last parts are held together under tension and not simply held in expanded or collapsed position under tension.

75 It is a further object of my invention to hold the last parts together by means employing a lever, with the parts constantly under tension.

80 It is a still further object of my invention to hold the parts of the last together under tension with the parts so arranged that the tension will assume its maximum when the parts are either in their fully expanded or fully collapsed position.

85 It is an additional object of my invention to provide the holding together of the parts under tension and to associate therewith a lever, the parts being so arranged that the tension will achieve its maximum at the 90 completely expanded or collapsed position of the last parts. It will be realized that the tension may be created by a variety of means which may be very compressible or expandable, and that the details of creating 95 this condition are not essential.

It is a further object of my invention to provide such mechanism to hold the parts of the last together under tension that it will not be necessary to have resilient links 100 or resilient anchor pins. Such means are eliminated and the same results are obtained.

105 It is a further object of my invention to provide the holding of such parts together under tension and the increasing of this tension at extreme positions together with means to lock the parts in extended position

by such tension means to resist the pressure, tending to collapse the last imposed on the bottom of the toe member in constructing the shoe thereon until such tension means is overcome by the operator breaking the last.

In the accompanying drawing I have shown a sectional view illustrating my invention.

10 In the drawing, 1 designates the heel part and 2 the toe part of a last divided as customary by an arcuate cut, as indicated, at 3, and moving about a center pin 4. Secured on the pin 4 is a triangular shaped plate 5, 15 one extremity of the base of which is secured to the heel part by a pin 6. The forward extremity of the base of this plate is pivotally connected by a pin 7 to a link 8 extending into the toe part 2 of the last. The forward 20 end of this link is pivoted by a pin 9 to a short link 10 which is in turn pivoted intermediate its length by a pin 11 to the toe part of the last. This same pin pivotally attaches the link to the forward extremity 25 of the base of a triangular plate 12. The other extremity of the base of this plate is pivoted on the bearing pin 4. To the apex of the plate 12 I pivotally attach a lever 13. This lever is provided on its under side with 30 a cam surface 14 while the upper side is in engagement with a spring 15 held under compression between it and a pin 16 in the toe part of the last.

With the parts in the position shown in full lines in the drawing,—that is to say, with the last in extended position, the pressure of the spring 15 upon the lever 13 is tending to swing the short link or lever 10 about the pivot pin 11, this movement drawing the link 8 to the right, thereby tending to shorten the distance between the pins 6 and 11 to hold the last parts in extended position under tension, the cam face on the lever 13 holding the parts locked in position. 45 When the last is collapsed the end of the link 10 moves past the raised portion on the cam face 14 and the action of the spring 15 is now in a direction to again shorten the distance between the pins 6 and 11, with 50 the result that the last parts are held in collapsed position under tension.

It will be apparent that I have provided a last structure wherein the last parts are held in extended position and in collapsed position under tension, thereby providing a structure which will successfully withstand accidental collapse or extension of the last parts when the same are in use in the manufacture of shoes. It will be seen also that 55 in my invention I provide a structure in which the force exerted on the last parts to

hold the last in extended and in collapsed position is of some magnitude, my improved construction being such, however, that this increase in force is provided without weakening the last. In other words, more power is available for holding the last parts in adjusted position due to my improved structure than is possible in lasts as now manufactured.

70 It will be seen also that I have provided a last structure wherein the last parts are held in extended position and in collapsed position under greatest tension. In other words, the tension under which the last parts are held to each other when the last is extended or when the last is collapsed, as the case may be, is greater than the tension under which the last parts are held when in an intermediate position.

75 Having thus fully described my invention, what I claim as new and desire to secure by Letters Patent is:

1. In a last of the divided type, the combination of a heel part and a toe part, a bearing pin for said last parts, a plate mounted on said bearing pin within the heel part of the last and having a portion thereof attached to said heel part, a link pivoted in the toe part of the last, a second link extending from said plate to one end of the first link, a member for connecting the first link to said bearing pin, and means for applying power to the first link adjacent the end thereof remote from the point of attachment of the first link to the second link to thereby maintain the last parts in extended position and collapsed position under tension.
